FAN UNITS FOR DRYING MACHINES

Christian H. Reumann, Olney, Pa., assignor to
The Philadelphia Drying Machinery Company,
Philadelphia, Pa., a corporation of Pennsylvania

Application October 26, 1934, Serial No. 750,122

11 Claims. (Cl. 34—19)

This invention relates to material treating machines in general, wherein the processing or other medium is continuously disseminated by means of a circulating fan, or series of circulating fans whereby the material treated is dried, conditioned or otherwise subjected to a systematic treatment productive of predetermined results.

More particularly the present invention has reference to "driers" or mechanical means for effecting the drying of materials, and it has for a primary object the provision of a fan assembly for drying enclosures which can be expeditiously installed, removed for repair, inspection or otherwise, without disturbing the material being dried or adversely affecting continuity in the drying operation.

Another object is to provide a drying equipment with a series of individual fan units, each of which may be introduced into, or retracted from, the drying enclosure with a minimum expenditure of time and labor.

A further object of the invention is to provide a fan unit of the character specified and for the purpose stated, which is simple in construction and includes but few parts of sturdy character, whereby said unit is not liable to derangement.

With the stated and ancillary objects in view this invention consists in certain structural features, combinations of elements and arrangements of parts which are exemplified in the embodiments of said invention herein described and illustrated, while the scope of the invention is particularly defined by the claims concluding this specification.

Before entering into a detailed explanation of my invention it is well to note that, heretofore, in order to replace, repair, or inspect the fans of standard drying machinery, it is customary to stop the machine, unload the material being dried from in front of the particular fan or fans requiring attention, and then remove the usual protecting screen, before access may be had to the fan or fans needing repair or other attention.

In the accompanying drawings:

Fig. I is a cross-section of a conventional form of drying machine, showing the improved type of fan unit in operating position relative to the drying enclosure; and also indicating said unit retracted, at the left-hand side of the view, in dot-and-dash lines.

Fig. II is a broken side view of the drying machine, or looking toward the right-hand of Fig. I.

Fig. III is a corresponding side view with the

fan unit removed and replaced by a blank panel closure-member; and,

Fig. IV is a cross-section illustrative of a modified form of the invention.

Referring more in detail to the drawings, a conventional drying machine of the "tunnel" type is comprehensively designated by the numeral 5, the same being divided into consecutive sections 6, in each of which the drying medium is independently circulated, while progressively advancing from the service inlet to an exhaust of such medium. The drying machine 5, in accordance with known practice, comprises a framework of vertical and horizontal sections 7, 8 and 8' respectively, with thermo-insulating material panels 9, and partitions 10, that define the consecutive treating sections 6; each such section being provided at one side of the machine with one or more hinged doors 11 affording access thereto, when necessary. In the particular showing, the drying machine 5, includes a tunnel or drying enclosure 12, through or into which suitable trucks 13, bearing trays 14 upon which the material to be dried is placed, are introduced or progressively advanced.

At the fan side of the machine 5, each drying section 6 is provided with an appropriate fan-ring or housing 15, suitably attached to the framework of the machine. All of the foregoing referred to parts are in accordance with known practice and are referred to generally by way of providing proper background for a clear understanding of the present invention.

In accordance with my improvements I construct a framework or fan support 16 including standard-section outer and inner verticals 17, 18 respectively, which are rigidly connected together in spacial relation by horizontal braces 19, 19'; and each said vertical 17, 18 is provided at its lower end with a freely-rotative castor or roller 20, whereby the fan support 16 may be wheeled about. The fan support verticals 17, 18 are of a height to be readily moved into the drying machine 5 and attached at their upper ends, by appropriate securing means 21 to parallel horizontals 8, in a manner obvious to those conversant with the art.

At a level intermediate the top and bottom of the fan support 16 there is firmly secured an inwardly-tapering truncate-casing 22, of thermo-insulating material. In the particular showing the casing 22 is rectangular in vertical section, and includes top, bottom, and side panels 23, 24, 25, respectively; with an inner thermo-insulated face-plate 26, that jointly form a substantially

tight enclosure or recess in which the fan motor 27 is mounted on the upper horizontals 19, with interposed thermo-insulating blocks or cross members 28. It is to be observed that the motor 27 is positioned so that the shaft 29 thereof projects through a corresponding orifice in the face-plate 26, alignedly with the axis of the fan ring or housing 16, hereinbefore referred to.

The type of fan 30 which I preferably use is 10 constructed with a double disc or paralleling concentric center-plates 31, diametrically somewhat larger than the inner end confines of the truncate casing 22, with suitably-shaped blades 32, secured between the peripheral portions of said plates. As a result of providing the fan 30 with 15 a central blank or "dead" area, larger than the confronting end of the casing 22, there is practically no air delivery by the fan 30 over said end, in that such delivery is solely through the 20 blades 32 annularly around the center plates 31, for a purpose later on again referred to.

Attention is now directed to the positioning of 25 the fan support verticals 17, 18, the latter or inner ones 18 being much closer together than the former, or against the smaller end of the truncate casing 22. This arrangement of the up- 30 rights 17, 18 not only adds rigidity to the fan mounting, but also materially facilitates ambient manipulation of the fan unit 16 as a whole, as will 35 be obvious without further explanation, while the support uprights 18 are provided at their upper ends with lateral braces 33, Fig. II, for connection to the machine frame horizontals 8 aforesaid. The outer area of the fan unit 16, above 40 and below the truncate casing 22 between the verticals 17, is fitted with thermo-insulating panels 34, so that when said unit is attached in place, in the drying machine 5, escape of any heated air or other treating medium is effectively prevented.

In cases where extremely high temperatures are essential in the drying machine 5, and in order to better protect the motor 27 against the ravages incident thereto, I preferably modify the 45 fan unit 16 as illustrated in Fig. IV. In this form of the invention I mount the motor 27a exterior to, or outside the confines of the casing 22a, the latter being, in this case, preferably made rectangular in all sectional planes; although it may 50 be, obviously, of tubular construction. To support the motor 27a, as just stated, I fit the unit with a suitable bracket including horizontal and oblique sections 35, 36 respectively. The fan 30a is mounted on an extension shaft 37, journaled in 55 a suitable bearing 38, secured within the inner end of the casing 22a, and connected to the motor shaft 29a by a flexible coupling 39; while the bearing 38 is supplied with lubricant by a tube 40, from an easily accessible oil cup 41, in an 60 obvious manner. In all other respects this form of my invention corresponds with the showing of Figs. I-III, and to obviate unnecessary repetitive descriptive matter, similar parts are designated by like reference characters with an added exponent "a".

Heater coils are conventionally indicated at 42, but it is to be remarked that the space between the fan 30 or 30a and the outside wall of the machine 5 is kept clear of such coils, pipes or 65 other means, that might interfere with the quick removal and insertion of the fan unit 16; while it will be seen that the thermo-insulating panels 34, 34a, casing 22 or 22a, and the face plates 26 or 26a, when the unit is in place, jointly become 70 part of the drying machine enclosing walls.

It will also be readily apparent that by opening the doors 11, and removing the securing means 21 or 21a, the entire fan unit 16, or 16a and fan 30 or 30a, can be wheeled out without shutting down the balance of the sections 6, or otherwise 5 interfering with continued operation of the machine. Furthermore, when the fan unit 16 or 16a is withdrawn, it may be readily replaced by a spare unit, kept for the purpose, and the machine 5 continued in operation at full efficiency: 10 or, if it is desired to operate said machine temporarily, while the withdrawn fan unit 16 or 16a is being repaired, a spare blank panel 43 may be substituted therefor, and the machine 5 continued in operation with but little decrease in its 15 efficiency, pending replacement of the removed fan unit 16 or 16a.

Attention is also directed to the mounting of the fan 30 directly on the shaft 29 of a standard type of motor 27, Figs. I-III, which does away 20 with the need for utilization of special motors having extended shafts and special bearings, to render possible location of the fan at some distance inwardly of the machine casing or outer wall; while in accordance with my invention the 25 motor 27 or 27a is rigidly and firmly supported.

The front of the casing 22 being open provides for easy access to the motor 27 if or whenever desired, while it also enables induced circulation of exterior air for cooling said motor; such induced circulation being materially enhanced by the inwardly tapering form of the casing 22. Furthermore the motor 27 or 27a may be provided with a built-in circulating fan 44, serviceable to draw air through the motor windings and discharge it into the casing 22 about the motor 27; such a fan being conventionally indicated by dot-and-dash outline in Fig. I; or a similar fan may be mounted on the motor shaft extension 37, Fig. IV, in an obvious manner. Again by use of stout 40 insulating blocks or cross members 28 for seating the motor 27, practically the only heat transmitted from within the drying machine 5 to the motor 27 is the negligible amount transferred by conductivity through the motor shaft 29. 45

Another advantage inhering to my invention is due to mounting the fan 30 on the motor shaft 29, and with practically only the insulating face plate 26 between said fan and the motor bearing, there is no loss in efficiency, as vibration is practically eliminated; while the tapering shape of the fan casing 22 materially assists circulation of the heated air in the drying enclosure 12 by gradually changing the course of the fan delivery, as indicated by the arrows in Fig. I, instead 50 of having it abruptly turned by the side walls of the machine 5. 55

Still further it is to be noted that the aperture in the face plate 26 or 26a is of a diameter as to snugly fit the shaft 29 or 37, so as to effect a 60 seal against exhaust of drying air from the enclosure 12 therethrough; or, should the motor 27 or 27a be reversed to similarly prevent entry of exterior air into said drying enclosure.

From the foregoing it is thought the merits and 65 advantages of this invention will be fully appreciated, and while specific embodiments of said invention have been illustrated and described, the same are not to be construed as limitative, as changes in the structural details and form of the 70 fan unit will naturally present themselves in adapting the invention to different types of drying equipment. Accordingly, the right is reserved to all such changes and variations, from the present disclosure, as are reasonably em- 75

braced within the scope of the following claims, or the prior art prescribes.

Having thus described my invention, I claim:

1. The combination in a drying machine subdivided to provide a plurality of drying enclosures, each of which has a sectional aperture, of a retractable unit adapted to close the aperture; said unit comprising a wheeled structure, means included in the structure jointly providing an outwardly-open truncate recess and closure for the sectional aperture, means supporting a motor in the truncate recess with its shaft projecting beyond said recess inner end wall, and a fan on the shaft projection with a central discous portion effective to prevent heated medium from the drying enclosure contacting the motor.
2. The combination in a drying machine subdivided to provide a plurality of drying enclosures, each of which has a sectional aperture, of a retractable unit adapted to close the aperture; said unit comprising a wheeled structure, means included in the structure jointly providing an outwardly-open truncate recess and closure for the sectional aperture, means supporting a motor in the truncate recess with its shaft projecting beyond said recess inner end wall, said truncate recess serving to induce a circulation of cooling medium about the motor, and a fan on the shaft projection with a central discous portion effective to prevent heated medium from the drying enclosure contacting the motor.
3. The combination in a drying machine subdivided into a series of drying enclosures with individual sectional apertures, of a retractable fan unit for each enclosure adapted to close the sectional aperture thereof, said unit comprising a wheeled structure, panel means defining in said structure an outwardly-open truncate casing and closure wall for the sectional aperture, bearings across said casing rigidly supporting a motor with its shaft projecting beyond the inner end wall thereof, a fan on the shaft projecting end in close proximity the truncate casing inner end, said fan having a central blank portion diametrically greater than the confines of the casing inner end, whereby heated medium from within the associated drying enclosure is prevented from contacting the motor, and means whereby the unit aforesaid is removably secured in the drying machine.
4. The combination of claim 3 wherein the wheeled structure comprises rigidly connected verticals and horizontals of standard sections, the combined closure panel and truncate casing consist of thermo-insulating panels, and the motor is supported on opposing horizontals with interposed blocks of heat insulating material.
5. The combination of claim 3 wherein the fan central blank portion comprises spaced discous members with the blade inner ends secured between the peripheral portions thereof.
6. The combination of claim 3 wherein the

wheeled structure comprises paralleling outer and inner verticals with connecting horizontals, said inner verticals being closer spaced than the outer, and lateral braces at the upper ends of the inner verticals whereby all of said verticals may be attached, by removable securing means, to paralleling frame members of the drying machine.

7. The combination in a drying machine subdivided into a series of drying enclosures with individual sectional apertures, of a retractable fan unit for each enclosure adapted to close the sectional aperture thereof, said unit comprising a wheeled frame structure of standard section verticals and connecting horizontals, thermo-insulating material panels defining in said structure a closure wall with an outwardly-open inset tunnel having the inner end closed, means supporting a motor in front of the tunnel open end with an extension of its shaft projecting through said tunnel closed end, a fan on the shaft extension projecting end having a central blank portion effective to prevent contact of heated air from within the drying enclosure contacting the motor, and means whereby the fan unit is removably secured in the drying machine.

8. The combination of claim 7 wherein the fan shaft extension is journaled in a bearing at the inner end of the inset tunnel, and is connected to the motor shaft by a flexible coupling.

9. In a drying machine subdivided into a series of drying enclosures with individual sectional apertures, a retractable fan unit for each enclosure adapted to close the sectional aperture thereof, said unit comprising a portable frame structure of verticals and horizontals, panels intervening the verticals and horizontals to define an outwardly-open recess and closure for the sectional aperture, means supporting a motor with its shaft projecting beyond the recess inner end, and a fan on the shaft projecting end with means effective to prevent heated medium from the associated enclosure contacting the motor.

10. A portable fan unit comprising a wheeled structure, means included in said structure providing an open-ended truncate-casing for a motor with panels above and below the open end to jointly define with the casing wall an aperture closure, said casing serving to induce and enhance circulation of cooling air about the motor and the latter having its shaft projecting through the closed end of the truncate-casing, and a fan on the shaft projecting end.

11. A portable fan unit as claimed in claim 10 wherein the wheeled structure includes spaced pairs of verticals with connecting horizontals, freely rotative elements at the lower ends of said verticals, and one pair of said verticals being closer spaced than the other to facilitate ambient manipulation of the unit as a whole.

CHRISTIAN H. REUMANN.
